UNITED STATES PATENT OFFICE.

ROSS V. CRAGGS, OF BALTIMORE, MARYLAND, ASSIGNOR TO RICHARD H. WRIGHT, OF DURHAM, NORTH CAROLINA.

CIGARETTE-FEEDING MECHANISM.

1,123,104.

Specification of Letters Patent. Patented Dec. 29, 1914.

Original application filed June 3, 1913, Serial No. 771,555. Divided and this application filed October 4, 1913. Serial No. 793,451.

To all whom it may concern:

Be it known that I, Ross V. CRAGGS, a citizen of the United States, residing at Baltimore, in the State of Maryland, have 5 invented new and useful Improvements in Cigarette-Feeding Mechanism, of which the following is a specification.

This invention relates to mechanism for feeding cigarettes, cigars, and other articles 10 to inclosures of any suitable type, and the primary object of the invention is to regularly assemble and discharge a predetermined number of cigarettes or other articles 15 from a hopper or other supply means carrying cigarettes or other articles in bulk to inclosures positively moved in sequence into receptive position relatively to the feeding mechanism, and to avoid choking of the cigarettes during feeding thereof from the 20 hopper to the assembling means and insure charging the inclosures with the same number of cigarettes in good condition.

The application embodies subject matter 25 divided out of my application Serial No. 771,555, filed June 3, 1913.

The invention consists in the construction and arrangement of parts more fully hereinafter described and claimed.

In the drawings:—Figure 1 is a top plan 30 view of a portion of a cigarette packaging machine showing the improved feeding or charging mechanism applied thereto; Fig. 2 is a front side elevation of the improved machine; Fig. 3 is an end elevation showing 35 the cigarette feeding or changing mechanism and operating mechanism therefor; Fig. 4 is a transverse vertical section taken in the plane of the line 4—4 of Fig. 1; Fig. 5 is a top plan view, on an enlarged scale, 40 of the means for assembling the cigarettes, a portion of the ejector therefor, the compression chamber, and a part of the mold wheel or disk; Fig. 6 is a top plan view of the compression chamber and compressor, and 45 a portion of the coöperating means for controlling the bunching and bodily expulsion of the bunches of cigarettes and showing a slight modification; Fig. 7 is an elevation 50 of a portion of the hopper and the slightly modified mechanism particularly shown by Fig. 6; Fig. 8 is an elevation of the assembling chamber for the cigarettes, particularly illustrating the partitions and the operating means therefor; Fig. 9 is a top 55 plan view, partially in horizontal section, of the assembling chamber as illustrated by Fig. 8; Fig. 10 is a transverse vertical section taken in the plane of the line 10—10 of Fig. 9; Fig. 11 is a transverse vertical section taken in the plane of the line 11—11 of Fig. 9; Figs. 12 and 13 are detail perspective 60 views respectively of one of the slide bars and one of the partitions associated with said bar and constituting part of the group of bars and partitions of the assembling 65 chamber.

The numeral 5 designates a table or support for all of the mechanisms and devices, and said table may be of any contour or dimensions and varied as hereinafter explained. The table is held at a suitable elevation above a floor or base by means of legs 6. Over the rear portion of the table 5 and held by uprights 7, 8, having bearings 10 at their upper extremities is a drive shaft 11 70 provided at one end with a loose pulley 12 adapted to be driven from a suitable power source, and having clutch members 13 and 14 coöperating therewith, the member 13 being associated with the pulley and the member 14 splined or otherwise shiftably mounted on the shaft 11 to rotate with the latter. The clutch member 14 will be controlled as 75 to its movement by the operator and has a groove 15 at its inner extremity engaged by 80 a yoke 16 carried at the upper end of a bell-crank lever 17 fulcrumed as at 18 on the outer side of the upright 7 and provided with a depending arm 19. In a bearing boss or lug 20 projecting from the feed end 85 of the table just below the clutch member 14, a crank shaft 21 is mounted and has on its rear end a crank 22 carrying a roller 23 at its free extremity which is in continual engagement with the inner side of the depending arm 19 of the bell-crank lever 17. The bell-crank lever 17 is held in the normal 90 position shown by Fig. 2, or so that the arm 19 will be in engagement with the roller 23 by a spring 24 seated in a portion of the 95 upright 7 above the fulcrum of the said lever. On the forward end of the crank shaft 21 a hand lever 25 is mounted and has a grip or handle 26 at its upper end 100 extending in a forward direction. The hand lever 25 is also provided with an inwardly extending catch finger 27 adapted to engage under an upstanding hook 28 at 105

the inner end of an arm 29 intermediately fulcrumed as at 30 to the table 5 and provided with a trip or pressure table 31 at its forward extremity engaged on its under side by a spring 32 which normally holds the said trip or pressure table 31 elevated and the upstanding hook 28 in engagement with the finger 27. The purpose of this particular clutch operating mechanism is to provide means for permitting the operator to quickly disengage the clutch member 14 from the member 13 of the band wheel or pulley 12 in the event that an improper feed of the cigarettes or disposition of the closures ensues. When the operator depresses the table 31 and releases the hook 28 from the finger 27, the hand lever 25 may be swung outwardly, thereby releasing pressure of the roller 23 from the lower extremity of the depending arm 19 of the bell crank lever 17 and permitting the spring 24 to come into play and force the clutch member 14 into engagement with the clutch member 13 of the band wheel or pulley 12 and thus set the machine in motion. By throwing the hand lever 25 inwardly, the finger 27 is caught under the hook 28 and the lower end of the arm 19 is pressed outwardly and consequently the upper arm of the bell crank lever is simultaneously forced inwardly against the resistance of the spring 24 to release the clutch member 14 and throw the machine out of operation, the hook 28 at the rear end of the arm 29 and the trip or pressure table 31 sustaining the clutch member 14 in the position shown by Fig. 2. It will be understood that the shaft 11 will also be provided with a suitable fly wheel adjacent to the band wheel or pulley 12, and the mounting of this shaft will be carried out to the best advantage relatively to the devices coöperating therewith and from which power is taken to drive the several parts of the machine, as will be herein-after explained.

The blank inclosures are regularly fed to and shaped in pockets 36 of a mold wheel or disk 35 and regularly positioned in succession by a step by step movement of the said wheel or disk to the improved cigarette feeding or charging mechanism 37. Any suitable mechanism may be used to impart to the mold wheel or disk a stepped rotation, and this wheel or disk is shown disposed horizontally, but it will be understood that a vertically arranged mold wheel or disk might be equally well employed.

After the blank of the inclosure or package is shaped and pressed into the pocket or seat 36, it is conveyed by the mold wheel or disk 35 to the cigarette feeding mechanism 37. The example illustrated shows the said mechanism as operating with a double row of five cigarettes in each row, which constitutes the ordinary package of ten.

This feeding mechanism embodies a hopper 92 having a bottom wall shaped as shown particularly by Fig. 7 and comprising a long gradual curve 93 at one side and a short curve 94 at the opposite side, both of these bottom curvatures merging into slight overhanging or inwardly projecting ribs or shoulders 95 and 96 continuing into under curved surfaces 97 and then merging into downwardly inclined converging walls 98 to an outlet opening 99. This hopper may be equipped with any suitable means for gaining access thereto and remains in fixed position on the table 5 to which it is suitably secured. The shape of the bottom of the hopper and the outlet walls as just explained prevents crowding and misshaping the cigarettes by pressure of the bulk above those adjacent to the outlet and insures a more perfect retention of the shape of the cigarettes or their preservation in approximately circular contour in cross-section. Beneath the discharge opening 99 at the base of the hopper 92 a box or casing 100 is located on a portion of the table 5. The box or casing 100 may be held fixed on the table 5 by any suitable means, and is open at its opposite ends and top portion, and therein is a plurality of six sliding bars 101, 102, 103, 104, 105 and 106 which are of such width as to snugly take up the space between the sides of the box or casing 100 but are free to shift or move between the said sides. These bars are mounted in such manner that a differential parallel sliding motion is imparted thereto, and this motion is effected through the medium of a motion transmitting lever 107, the bars at one end of each being formed with a horizontal slot 108, and when the bars are assembled all of the slots 108 coincide, thus forming an elongated seat for the reception of the lever 107. The lever 107 is intermediately fulcrumed as at 109 to one of the bars, as shown bar 104; and the opposite ends of the lever or 110 the portions thereof on opposite sides of the fulcrum or fulcrum pin 109 are constructed with elongated slots 110 and 111, and extending vertically through the slotted ends of the bars are pins 112 which pass through the slots 110 and 111 of the lever 107. The pins 112 are similar to the fulcrum pin 109, said pins terminating at their upper and lower ends coincidently with the upper and lower sides of the several bars 101 to 106 inclusive. The bar 104, or that through which the fulcrum pin 109 extends, may be properly termed the intermediate governing bar, and at one end this bar is provided with a buffer 113 which is preferably 125 spring-actuated, as shown by Fig. 9, to engage an adjustable stop screw 114 in line therewith and carried by an angle arm 115 forming part of the first bar 101, the latter bar being extended beyond the adjacent 130

bars and having the arm 115 carried thereby. As shown by Fig. 5, the buffer 113 is carried by the same bar as shown by Fig. 9 and acts as a stop means or a limiting device 5 for the movement of the slide bars 101 to 106 in one direction. The bar 103, as shown by Fig. 5, carries an extension spindle 116 movable through a suitable goose neck 117, said spindle being screw-threaded and 10 carrying an adjusting nut 118 between which and the inner depending extremity of the goose neck a coiled spring 119 surrounds the spindle and serves as a yielding buffer and also to impart a partial return 15 movement to the group of slide bars. In the form of this mechanism as shown by Fig. 9, the bar 104 on the end opposite that carrying the buffer 113 is provided with an extension spindle 120 which loosely moves 20 through an angle plate 121 and is provided with an adjusting nut 122, the spindle having a spring 123 surrounding the same between the angle plate and the adjacent end of the bar 104. The first bar 101 is also formed 25 with an outwardly extending bracket or connecting arm 124 for attachment thereto of a connecting rod or lever 125 by which movement is imparted to the whole series of bars. The slide bars 101 to 106 carry a plurality of 30 upright partitions or walls 126, 127, 128, 129, 130 and 131 which extend transversely thereover, as clearly shown by Figs. 5, 9, 11 and 12. The partitions or walls 126 to 131 engage different portions of the bars and each 35 partition has a depending attaching flange or member 132, as shown by Fig. 13, which fits in a corresponding slot 133 opening upwardly through the upper edge of each bar. The flanges or attaching members 132 and 40 the slots 133 are located in different positions relatively to the several partitions and bars, and considering for example that Fig. 12 shows bar 102 and Fig. 13 illustrates partition 127 attached to said bar, it will be ob- 45 served that the member or flange 132 stands inwardly far enough from the nearest end of the partition or wall 127 to leave a clearance at the under edge of said partition or wall of such length as to permit the said 50 nearest end of the partition to project over the outermost bar 101 at one side and the upper edge of the adjacent side of the box or casing 100.

The flange or member 132 of the wall or 55 partition 126 will be nearer the one end of the said partition or wall as is shown by Fig. 13, and the slot 133 in the bar 101 will be located in advance of the corresponding slot in the bar 102, and so on through the 60 whole series of bars. The flanges or members 132 of the several partitions or walls will gradually increase in their distance as to location from, for instance, the right end of the partition, as shown by Fig. 13, to- 65 ward the opposite end throughout the series

of partitions or walls, and the parts of the partitions or walls on opposite sides of the flanges or members 132 will be loosely disposed over the bars, or in other words, the said partitions or walls will be individually 70 attached to the bars and have loose movement with relation to the remaining bars or be free to move over the latter bars. The partitions or walls 126 to 131 remain in upright position at all times or do not tilt 75 either to the right or left, and the end partitions or walls 126 and 131 are respectively formed with upper ledges 132^a and 133^a which extend in opposite directions in planes at right angles to the said partitions or walls 80 and cover the opposite extremities of all of the bars 101 to 106 except the angular extension or elbow 115 of bar 101 and the arm 124 of the same bar. These ledges 132^a and 133^a fit snugly under the base of the hopper 85 on opposite sides of the outlet opening 99 and move with the partitions carrying the same and therefore shift in opposite directions under the hopper and serve to alternately guide or direct the cigarettes into the 90 spaces between the partitions or walls 126 to 131. In the position of the mechanism as shown by Fig. 4, it will be seen that the ledge 133^a is projected some distance into the outlet opening 99 of the hopper and the 95 cigarettes gravitating toward the said outlet opening will rest on this ledge, but when the partition or wall carrying the ledge, together with the corresponding bar of the partition, is shifted toward the left, the 100 cigarettes will be pushed off this ledge and correspondingly the opposite ledge 132^a will move into the outlet opening and receive cigarettes thereon, and said ledge 132^a will be 105 cleared of cigarettes when the bars are moved toward the right or into normal position. As a minute structural advantage the ledges 132^a and 133^a at their points of intersection with the partitions 126 and 131 are formed with 110 regularly curved bends so as to avoid sharp angular corners and also facilitate the movement of the cigarettes downwardly into the adjacent spaces or pockets between the partitions or walls, with material advantage 115 in preserving the cross-sectional contour of the cigarettes. The opposite extremities of the partitions or walls 126 to 131 are fully open for engagement therewith of ejecting means at one side and free liberation by longitudinal movement of the cigarettes at 120 the opposite side, and thus the cigarettes may be readily discharged from between the partitions, and it will be seen that these partitions with the bars carrying the same form as assembling chamber or receiver beneath the hopper. It will also be understood that the number of bars and partitions may be varied to form packages containing more than ten cigarettes or cigars, as the case 125 may be.

When the first bar 101 is drawn to the right by means of the connecting rod or lever 125, the horizontal shifting lever 107 through the pin connection hereinbefore described is similarly moved at the end adjacent to and coöperating with the said bar 101, and the succeeding bars 102 and 103 are moved relative distances in the same direction or toward the left, in accordance with their distance from the fulcrum pin 109, and the bars 105 and 106 are shifted toward the right, the bar 104, through which the fulcrum pin 109 extends or to which the said lever 107 is pivotally attached, remaining for the time being without sliding movement, and by this movement of the bars all of the partitions or walls carried by the bars except that engaging the bar 104 are moved in directions corresponding to the movement of their bars, or the partitions or walls carried by the bars 102 and 103 are moved to the left and the partitions carried by bars 105 and 106 are moved to the right, thereby increasing to the distance of movement of the bars carrying the same and permitting the cigarettes to roll down and fill the spaces or pockets between the partitions without crushing or misshaping the cigarettes, sufficient distance being left by predetermined adjustment between the several partitions when the movement thereof takes place to permit the cigarettes to fall easily into the space or pockets between the partitions without crowding or undue pressure of the cigarettes, and this increase of space permits the cigarettes to roll relatively to each other and become properly disposed between the partitions. The movement of the bar 101 to the left continues until the stop screw 114 strikes the buffer 113, and when this engagement ensues, all of the bars, including bar 104 to which the lever 107 is fulcrumed, are bodily moved to the left by a continuation of the drawing action of the bar 101 through the medium of the connecting rod 125. This bodily movement of all of the bars is against the resistance of the spring 123, and during such bodily movement the stem 116, as shown by Fig. 4, is drawn through the inner extremity of the goose neck 117 against the resistance of the spring 119, or as shown by Fig. 9 the stem 120 is pushed through the angle bracket 121 against the resistance of the spring 123 and the nut 122 recedes slightly from the portion of the angle plate normally engaged thereby. This bodily movement of the bars varies the position of the partitions or walls under the hopper so that all of the spaces or pockets between the partitions will become properly filled with cigarettes from the hopper and a sufficient agitation or displacement of the cigarettes in

the hopper will ensue to maintain the cigarettes in close relation or free exit condition at the outlet of the hopper. This bodily movement is of comparatively short duration and the return stroke of all the bars, which is brought about by the spring 123, causes a settling or jogging action to be imposed on the cigarettes between the partitions and a continual movement toward the right, which will be imparted by the connecting rod 125, will shift or slide the bar 101 toward the right and restore the remaining bars 102, 103, 105 and 106 to normal position and correspondingly shift the partitions so as to assume a closer relation to the cigarettes therebetween and positively hold the cigarettes in rows for practical ejection from the receiver or assembling chamber. The degree of movement of the several bars 101 to 106 may be regulated by adjusting the screw 114 so as to project closer to or at a greater distance from the combined stop and buffer pin 113, and similarly the screw 122 may be adjusted on the stem 120 to vary the bodily movement of all of the bars and the partitions. The adjustment of the screw 114 will regulate the spacing or separation of the partitions 126 to 131. The bodily movement of all the bars and partitions is, as a matter of course, transmitted to the ledges 132^a and 133^a, and the latter are given opposite reciprocating or sliding movements under the bottom of the hopper 92 to alternately receive cigarettes that may fall thereon and cleared of the cigarettes by the opposite lower terminals of the wall the outlet 99 of the hopper having close coöperation with the said ledges. The connecting rod 125 extends forwardly and is connected to the upper member of a crank arm 126^a journaled on a rod 127^a, see Fig. 2, the lower member of said crank arm engaging a cam 128^a which is suitably grooved or shaped to give the proper motion to the bars 101 to 106 and the partitions carried thereby to preliminarily separate the partitions and then bodily move all the bars and partitions as hereinbefore explained. The cam 128^a is fixed to a shaft 129^a journaled in hangers 130^a and 131^b depending from the under side of the table 5. This shaft 129^a has a sprocket wheel 132^b thereon over which a chain belt 133^b is trained and passes upwardly through the table and also runs over a sprocket wheel 134 on the shaft 11. It will be understood that the chain belt 133^b will be engaged by suitable idlers to keep the parts thereof in proper operating condition.

As a preferred specific detail of construction the box or casing 100 is formed as a part of the table 5 or in a suitable extension of the latter, and it will be understood when the number of bars and partitions is in-

creased the box or casing will be made correspondingly wider or of such transverse extent as to provide for the introduction and operation therein of the additional bars and partitions. It will also be understood that the hopper 92 is slightly greater in width than the standard length of cigarettes, and in placing the cigarettes in the hopper they will be disposed with their ends adjacent to the opposite side walls and by this means they will settle and roll down to the outlet 99 in approximately regular condition or in such position as to be disposed between the partitions 126 to 131 for practical ejection. Incidentally, practice has demonstrated that with the feeding mechanism as just described the ordinary hopper with the inclined sides causes the cigarettes contained therein to have a tendency to arch over a little away from the ledges 132^a and 133^a, and thus prevent the descent of the cigarettes and outlet into the receiver or assembling chamber below. To obviate this defect it is preferred that one side of the hopper be given a greater inclination than the opposite side, as shown particularly in Fig. 7 so that the movement produced by the feeding mechanism below for the movement and reciprocation of the bars 101 and 106, and the partitions or walls 126 and 130 is effective more directly on the comparatively few cigarettes adjacent to the outlet 99 and below the projections 95 and 96 of the opposite hopper walls. Furthermore, these projections serve to support the weight of the cigarettes above the same and prevent crushing or jamming of the cigarettes on the ledges 132^a and 133^a, as heretofore stated.

The cigarettes in the receiver or assembling chamber are pushed out at regular intervals through the medium of an ejector 135 comprising a plurality of spaced fingers 136 corresponding to the number of spaces between the partitions or walls 126 to 131, these fingers 136 being of such length as to fully push the cigarettes outwardly from between the partitions or walls and of such vertical extent as to engage the two rows of cigarettes of five each between the partitions. The fingers 136 project forwardly from a common web 137 pivoted at its outer end as at 138 to a support or slide 139 mounted in a guide 140 projecting outwardly from the table 5. By pivoting the outer end of the ejector 135, the latter may be drawn over or raised from operative position at times when it may be found necessary to temporarily dispense with the operation of the ejector in order to rectify some slight error in any of the cigarettes or for any other purpose without stopping the operation of the remaining mechanism. When the ejector 135 is thrown over in an outward direction it may continue to reciprocate as long as desired without performing its ejection function. The ejector 135 is operated by a suitable cam 141 mounted on the shaft 129^a through the medium of a slide bar 142 having an outer forked end 143 loosely movable over said shaft 129^a and also provided with a roller 144 to engage a suitable groove construction in the cam 141. The inner end of the slide bar 142 is provided with a rack 145 to engage a pinion 146 on the lower end of a shaft 147 having bearing in a hanger 148 depending from the table 5, as clearly shown by Fig. 3. On the outer end of the shaft 147 a gear or pinion 149 is secured and disposed in horizontal position and held in continual mesh with the support or slide 139 carrying the ejector, said support or slide 139 having a rack 150. A reciprocating movement is imparted to the slide bar 142 regularly in opposite directions by the cam 141 and through the rack 145 and pinion 146 the shaft 147 is regularly rotated in opposite directions and correspondingly the gear or pinion 149 on the upper extremity of said shaft is reversely rotated and consequently the slide 139 is shifted inwardly and outwardly to move the ejector 135 into and through the receiver or assembling chamber for the cigarettes, and then outwardly to clear the said receiver or chamber to permit the latter to recharge by the operation of the mechanism hereinbefore specified.

It will be understood that the movement of the slide or bar 142 will be intermittent or will take place at regular intervals so that the receiver or chamber under the hopper 92 may be practically charged with cigarettes between the periods of ejection. The inner ends of the fingers 136 squarely strike the adjacent ends of the cigarettes between the partitions or walls 126 to 131 and as the cigarettes are loose between the partitions they will be pushed longitudinally with an easy motion and all equally without the least deviation and are discharged into a pressure chamber 151 as clearly shown by Figs. 1 and 5. The pressure chamber 151 is provided in a carrier frame comprising an inner transverse end wall 152 and a side wall 153 at right angles to the wall 152, the side wall 153 being movable under a guide 154 supported on the table 5 and snugly engaging said wall 153 to prevent too loose movement or displacement of the carrier as a whole out of a true line of travel in accordance with a predetermined arrangement of the several parts embodied in this particular construction. In fact, the top wall of the guide 154 has sufficient frictional engagement with the side wall 153 to render the movement of the carrier at all times accurate. Projecting from the outer end of the wall 153 is a right angular guide or arm 155 forming a bearing as well as a

contributing stop projection, and at an intermediate point the bearing arm 156 extends into the receiving chamber.

A plunger stem or rod 157 is slidably mounted in the arm 155 and an arm 156, and between the said arms a spring 158 surrounds the rod 157 and is adjustable through the medium of a set sleeve 159 also disposed on the rod 157. The rod 157 has a plunger 160 fixed to its inner end which operates through the reciprocation of the said rod to first slightly compress and closely dispose the cigarettes discharged into the chamber 151 and then bodily move the cigarettes to a point of delivery from the chamber, as will be presently explained. The outer end of the rod 157 has a head 161 secured thereto and movably attached to the head is a connecting rod 162. As hereinbefore stated, the rod 157 is free to reciprocate or slide in the arms 155 and 156 and when the said plunger rod 157 is drawn outwardly and the plunger 160 approaches the arm 156, the head 161 recedes from the outer side of the arm 155, and the rod 157 is given a slight resilient action in view of the spring 158 surrounding the same between said sleeve 159 and the arm 155, and consequently on the return or inward strokes of the plunger 160 a preliminary resilient or yielding operation is given to the said plunger by the spring 158 so as to yieldingly compress the charge of cigarettes in the chamber 151 without unduly forcing the cigarettes or misshaping the same, and this preliminary pressure continues until the inner end of the head 161 abuts against the arm 155, when a continued inward movement of the connecting rod 162 then shifts the entire carrier including the plunger 160 and rod 157 together with the charge of cigarettes to a point of discharge which will be hereinafter explained.

The chamber 151 is provided with a bottom wall 163 and the charge of cigarettes is shifted thereover when the carrier moves to a point of delivery or discharge. The carrier is limited in its outward movement or is restricted as to its outward stroke by an adjusting screw 164 held by a suitable angle plate, as 165, or other analogous means, and the said screw 164 is adjustable so as to vary the movement of the carrier in an outward direction in accordance with the dimensions of the cigarettes forced into the chamber 151. The connecting rod 162 is movably attached at its outer end to the upper member of a bell crank lever 165^a mounted on the supporting shaft 127^a adjacent to the inner side of the hanger 131, as shown by Fig. 2, and the lower member of said bell crank 165^a is provided with a suitable roller or analogous means 166 engaging the cam 167 on the shaft 129^a.

It is desired to be understood that the cams 141, 128^a and 167 will all be channeled or grooved to impart to the mechanism with which they directly coöperate a regularly timed operation in accordance with the several progressive steps in feeding the cigarettes, and discharging the latter in regular quantities, and in the operation of the carrier embodying the walls 152 and 153 together with the plunger 160 and rod 157 it will be understood that the cam groove or channel in the cam 167 will be of such contour as to permit the inward yielding pressure movement of the plunger 160 against the cigarettes and also permit said plunger to be slightly drawn outwardly after the slide as an entirety has reached the limit of its outer stroke, and by this means the plunger 160 is always automatically operated to be ready for successive yielding compression strokes in relation to the successive charges of cigarettes delivered into the chamber 151. The charges of cigarettes after compression and close assemblage thereof are regularly moved by the carrier over a discharge table 168 having therein a pocket 169 of such dimensions as to readily receive but hold the cigarettes in the charge in close assembled relation, and at the bottom of the table 168 spring-controlled retaining lips or flaps 170 are located to hold the charge of cigarettes in the pocket 169 with a comparatively small resistance to the expulsion of the cigarettes from this pocket. The carrier with the charge of cigarettes in moving over the table 168 and pocket 169 at the same time, as shown by Figs. 1 and 2, shifts under a discharging plunger 171 at the lower end of a stem 172 which is adjustably mounted in a forwardly projecting horizontally disposed arm 173, said arm 173 being secured to the lower extremity of a vertical reciprocating rod 174 having a closed yoke 175, see Fig. 2, reciprocatingly mounted over the shaft 11 and carrying a roller 176 at its upper extremity which engages the groove of a cam 177 secured to the said shaft 11. The horizontal arm 173 while being held rigidly in a horizontal plane reciprocates equally with rod 174, and this arm is adjustable on the said rod, and for the purpose of conveniently adjusting the same a vertical socket 178 is provided at the rear end of said arm to receive the lower end of the rod 174, the socket 178 being held in fixed adjustment by means of a suitable set screw 179, as shown by dotted lines in Fig. 2. By adjusting the arm 173, the vertical movement of the discharging plunger 171 may be regulated to accommodate the bulk of the charges of cigarettes with which it coöperates or to render it effective in operation with cigarettes that may have variations in diameter.

As hereinbefore explained, the retaining flaps or lips 170 located at the opposite ends

of the discharge pocket 169 hold the cigarettes up until they are released or discharged by the plunger 171, and said plunger moving downwardly engages the top 5 row or layer of the cigarettes and forces the charge bodily through the pocket 169 into the inclosure in the pocket 36 of the mold wheel 35, which will then be located immediately below the table 168. After this 10 discharge of the cigarettes has been effected through the table 168 the plunger 171 immediately rises or is moved upwardly through the medium of the mechanism for operating the same, and the carrier embodying the plunger 160 recedes or moves outwardly and the chamber 151 is cleared for a 15 subsequent charge of cigarettes, when the same operation will be carried out and continued successively and all the charges of 20 the cigarettes delivered into the chamber 151 from the receiver or assembling chamber under the hopper 92.

As shown by Figs. 6 and 7, the discharge plunger is connected to and moves with the 25 carrier, and connected to and movable with the carrier is an upright 180 having the yoked end 181 supporting a roller frame 182 in which a roller 183 is centrally mounted, and in this instance the discharging 30 plunger 184 is disposed in an enlarged inclosure 185 which forms a receiving chamber for the successive charges of cigarettes, and rising from the said plunger is a stem 186, said stem 186 projecting upwardly through 35 the center of the yoked extremity 181 of the upright 180 and operatively associated with the roller frame 182. The discharge plunger 184 may be held in normally elevated position by a spring, as at 186^a, and the inclosure 40 185 moves over a table 187 having a pocket 188 therein similar to that shown by Figs. 1 and 2 and provided with spring-actuated retaining flaps or lips 189, the charge of cigarettes being discharged through the table 187 45 into one of the pockets 36 of the mold wheel below. When the inclosure 185 with the plunger 184 therein rises over and coincides with the pocket 188 of the table 187, the roller 183 engages with the forward extremity of a depressing arm 190 adjustably 50 mounted on a vertical reciprocating rod 191 which corresponds to the rod 174, shown by Fig. 2, and having a similar operation through the medium of the cam 177 heretofore described. When a proper registration 55 of the inclosure 185 over the pocket 188 is accomplished, the arm 190 immediately descends and presses on the roller 183, and stem 186 together with the plunger 184 are 60 depressed to expel the charge of cigarettes. After the discharge of the cigarettes has been effected, the arm immediately rises, the stem 186 and plunger 184 resume their normal positions, and the carrier with the plunger and stem as well as the inclosure 186 65

recede or move outwardly ready to take another charge of cigarettes from the receiver or assembling chamber under the hopper 92. The discharge plunger and its operating means may be indefinitely varied or 70 modified. While it will be seen that it is only necessary to have the plunger operate at proper intervals to depress and discharge or expel the successive charges of cigarettes into the mold wheel or inclosures carried by 75 the successive pockets of the latter, and while it is preferred to use a horizontally disposed mold wheel, it will also be understood that the same mechanism might be adopted in connection with a vertical mold 80 wheel or any other analogous device for receiving charges of cigarettes at timed intervals.

After the inclosures have been charged with cigarettes, they are adapted to be 85 moved successively by the mold wheel or disk 35 to other instrumentalities for completing the inclosures for commercial vending, as explained in my application herein-before mentioned. 90

What is claimed is:

1. In a machine for packaging cigarettes and other articles, the combination of a rotatable mold wheel carrying inclosures, mechanism for charging the inclosures with 95 cigarettes and embodying a fixed hopper, a receiver under the hopper comprising a plurality of differentially separable partitions which are individually and unitedly movable to prepare a predetermined charge of 100 cigarettes, a carrier for the charges of cigarettes, an ejector for discharging the cigarettes from the receiver into the carrier, and a plunger for pressing the charges of cigarettes from the carrier into the inclosures of 105 the mold wheel.

2. In a machine for packaging cigarettes and other articles, the combination of a rotatable mold wheel having means for receiving and holding inclosures, mechanism for feeding charges of cigarettes to the inclosures in the mold wheel comprising a fixed hopper, a reciprocating assembling chamber adjacent to the bottom of the hopper embodying a plurality of upright partitions having means for imparting a differential separation thereof and also for bodily moving said partitions as a group under the hopper while remaining in an upright position, and mechanism for ejecting the successive charges from the assembling chamber from between the partitions, exerting an assembling pressure on the successive charges from the chamber and pressing these charges into the inclosures of the mold wheel. 115 120 125

3. In a machine for packaging cigarettes and other articles, the combination of a mold wheel having a step rotation and provided with pockets to successively receive inclosures, cigarette feeding mechanism consist- 130

- ing of a fixed hopper, a reciprocating assembling chamber at the bottom of the hopper for predetermined charges of cigarettes and embodying partitions which remain upright and have a differential separating movement imparted thereto and a reciprocating movement as a whole under the bottom of the hopper, and mechanism for discharging the cigarettes from the assembling chamber, exerting an assembling pressure on the charges of cigarettes and depositing the charges in the inclosures of the mold wheel.
4. In a feeding mechanism of the class specified, a hopper with a bottom outlet, an assembling chamber adjacent the hopper outlet having normally separated partitions always maintained in upright position and structurally continuous from their upper to their lower ends, and means for shifting the partitions as a whole a greater distance apart and restoring them to normal position while they are maintained in upright position.
5. In a feeding mechanism of the class specified, a hopper with an outlet, an assembling chamber adjacent to said outlet provided with spaced partitions having a rigid structure throughout their vertical and transverse extent, and means for bodily shifting the partitions away from and toward each other.
6. In a feeding mechanism of the class specified, a hopper with an outlet, an assembling chamber adjacent to said outlet provided with spaced rigid upright partitions, and means for bodily shifting the partitions to modify the spaces between them while they are maintained in upright positions.
7. In a feeding mechanism of the class specified, a hopper with an outlet, and an assembling chamber adjacent to said outlet provided with division devices rigid throughout their full vertical and transverse extent having means for automatically varying the normal spaces between them.
8. In a feeding mechanism of the class specified, a hopper with an outlet, and an assembling chamber adjacent to said outlet provided with division devices rigid throughout their vertical and transverse extent having means for automatically imparting a differentiating bodily movement thereto to vary the normal spaces between them.
9. In a feeding mechanism of the class specified, a fixed hopper with an outlet, and an assembling chamber adjacent to said outlet provided with bodily movable division means, said division means being rigid throughout their vertical and transverse extent and individually differentiating in their movement.
10. In a feeding mechanism of the class specified, a hopper with an outlet, an assembling chamber adjacent to said outlet, and reciprocating devices carrying rigid partitions extending into said chamber, the reciprocating devices having individual differentiating movements.
11. In a feeding mechanism of the class specified, a hopper with an outlet, an assembling chamber adjacent to said outlet, and devices having individual differentiating reciprocation and carrying upright partitions extending into said chamber and rigid throughout their vertical and transverse extent.
12. In a feeding mechanism of the class specified, a hopper with an outlet, an assembling chamber adjacent to said outlet, devices having individual differentiating reciprocation and carrying upright rigid partitions extending into said chamber, and means for adjusting said devices to vary the reciprocation thereof.
13. In a feeding mechanism of the class specified, a hopper with an outlet, an assembling chamber adjacent to said outlet, upright rigid partitions extending into the chamber, and means for shifting the said partitions and also vibrating the partitions as a whole to give them a quick shaking movement.
14. In a feeding mechanism of the class specified, a hopper with an outlet, rigid spaced partitions extending into the hopper, means for bodily reciprocating the partitions and varying the width of the spaces between them, and means for imparting a quick shaking movement to the partitions.
15. In a feeding mechanism of the class specified, a hopper with an outlet, an assembling chamber adjacent to said outlet provided with spaced division devices, and means for reciprocating the chamber and its complemental parts as a unit relatively to the outlet of the hopper and for individually and bodily shifting the division devices away from and toward each other.
16. In a feeding mechanism of the class specified, a hopper with an outlet, an assembling chamber adjacent to said outlet provided with spaced division devices, and means for reciprocating the chamber and its complemental parts as a unit relatively to the hopper outlet and for individually and bodily shifting the division devices and also imparting thereto a quick shaking movement.
17. In a feeding mechanism of the class specified, a hopper with an outlet, an assembling chamber having spaced partitions structurally continuous from their upper to their lower ends and provided with means for individually and bodily shifting them to modify the spaces therebetween, and an expelling device having parts movable through the chamber between the partitions.
18. In a feeding mechanism of the class

specified, a fixed hopper with an outlet, an assembling chamber having spaced partitions provided with means for individually and bodily shifting them to modify the 5 spaces therebetween, and a reciprocating expelling device having parts movable through the chamber between the partitions, the expelling device being hinged for throwing it upwardly and outwardly to prevent engagement thereof with the chamber without

stopping the movement of the expelling device.

In testimony whereof I have hereunto set my hand in the presence of two subscribing witnesses.
